A CORPORATION OF ILLINOIS.

SPINNING MACHINE.

Application filed May 28, 1918. Serial No. 237,191.

In order to facilitate the mechanical finding of the free end of the yarn on a filling bobbin or a warp bobbin, it is desirable to spin enough coils of yarn on the upper end 5 of the bobbin to form a small mass above the main yarn mass, which coils of yarn may be grasped by a suitable device and stripped off the bobbin. These coils of yarn, of course, are connected by a strand of yarn to 10 the main yarn mass, and when stripped off the bobbin they are followed by said strand, the latter constituting the found end.

One of the objects of the present invention is to provide improved mechanism for 15 operating the spinning machine to produce a small yarn mass upon the upper end of each bobbin.

Before removing the full bobbins from the spinning frame, it is customary to spin a few coils of yarn upon the lower end of the bobbin in order that when the bobbin is doffed these coils of yarn shall slip off onto the spindle and afford means for attaching the yarn to the new bobbin. The coils of 20 yarn upon the lower end of the bobbin are spun after the yarn has been coiled about the upper end of the bobbin and thus the coils at the upper end of the bobbin are connected to those at the lower end of the bobbin by a strand of yarn. If the proper number of coils have been wound about the 25 lower end of the bobbin, they will slip off the bobbin and the connecting strand will be broken in the doffing operation; but, if an excessive amount of yarn has been wound 30 about the lower end of the bobbin, some of that yarn will remain wound about the lower end of the bobbin when the bobbin is doffed and, therefore, the strand connecting 35 the upper coils to the lower coils will not be broken. When such a bobbin is placed in a weft-replenishing loom provided with an end-finding device for stripping the upper coils off the bobbin, various difficulties may 40 arise. If the surplus lower coils unwind when the upper coils are stripped off the bobbin, said surplus coils will form a strand of greater or less length which trails along with the found end; and if this strand is of 45 excessive length it will reach into the cloth 50

and cause a defect therein. If the strand connecting the upper and lower coils should break in the end-finding operation, the yarn remnant on the lower portion of the bobbin will either break the weft thread or become 55 woven into the cloth. Or the found end may break in the end-finding operation while being unwound beneath the strand connecting the upper and lower coils.

It is necessary that the strand extending 60 from the front drawing roll to the traveler shall be somewhat slack, in order, principally, to allow the bobbin to be lifted until the strand extending between the traveler and the bobbin assumes such an angle that the 65 coils on the lower end of the bobbin will slide off. If, however, too much slack yarn is spun, there may result excessively large kinks which may catch on the thread guide or other parts and cause breakage of the 70 yarn, or the kinks may be unable to pass through the traveler or the thread guide and thus cause breakage of the yarn when the machine is again started.

The method heretofore used in spinning a 75 doffing coil upon the lower end of the bobbin and in obtaining the necessary slack has consisted in lowering the ring rail to the doffing position and then stopping and restarting the machine repeatedly and in quick succession by shifting the driving belt off and onto the drive pulley. When the ring rail reached the doffing position, some yarn would be wound around the lower end of the bobbin and during the succeeding operation of the machine more or less slack yarn 80 would be spun. In practice, this method of spinning yarn on the lower end of a bobbin and providing slack yarn did not produce satisfactory results. In restarting the machine the belt would sometimes be allowed to remain upon the drive pulley so long that the speed of the machine would increase to the point where some or all of the slack yarn 85 previously spun would be wound upon the lower end of the bobbin, thereby placing an excessive amount of yarn on the lower end of the bobbin and making it necessary to spin more slack yarn to take the place of that which had been unintentionally wound 90 95

on the bobbin. The spinning of slack yarn might also continue until excessively large kinks had formed in the yarn between the traveler and the drawing rolls. The method 5 just described for putting the machine in condition for doffing not only was unsatisfactory in results, but also was laborious and required some skill and considerable attention on the part of the operator.

10 One of the objects of our invention is to provide means for automatically operating the spinning machine to wind the correct amount of yarn upon the lower end of the bobbin and to spin the proper amount of slack yarn, thus also simplifying and reducing the work of stopping the machine in condition for doffing.

In the accompanying drawings, Figure 1 20 is a fragmental side elevation of a spinning machine embodying the features of our invention. Fig. 2 is a fragmental transverse sectional view showing, more or less diagrammatically, the drawing rolls, the thread-board, the bobbin, and the ring rail.

25 Fig. 3 is a sectional view, upon an enlarged scale, taken in the plane of line 3-3 of Fig. 1. Fig. 4 is a fragmental longitudinal section taken in the plane of line 4-4 of Fig. 7, showing the end of the machine opposite to that illustrated in Fig. 1. Fig. 5 is a detail view of a lock to hold the ring rails in doffing position. Fig. 6 is a transverse sectional view taken in the plane of line 6-6 of Fig. 4. Fig. 7 is a fragmental 30 horizontal section on line 7-7 of Fig. 4. Fig. 8 is a view looking from the left-hand side of Fig. 4. Fig. 9 is a fragmental plan view of the end of the machine shown in Fig. 1. Fig. 10 is a view of the yarn package produced by the machine. Fig. 11 is a detail view of one of the members comprised in the mechanism. Fig. 12 is a fragmental end elevation. Fig. 13 is a fragmental detail view. Fig. 14 is a fragmental side elevation. Figs. 15 and 16 are detail views of 35 a certain element comprised in the machine.

The creel is not illustrated in the drawings, as the invention has no particular reference thereto.

40 Our improvements have been shown as embodied in a ring spinning machine of ordinary construction, but it will be understood that the invention is not limited to any particular form of ring spinning machine.

45 The machine comprises spindles 1, the bases of which are mounted in the upper flanges of the ladder rails 2. 3 are the whirls on the spindles. 4 are bands extending from the drum 5 to the whirls 3. The 50 drum 5 is fixed upon the main shaft 6. The ring rails 7 are connected to the upper ends of lifting rods 8, the latter being slidably mounted in the ladder rails 2. To the lower ends of the lifting rods 8 are attached shoes 9 (Fig. 1) that rest upon roller studs 10

carried by arms 11, said arms being located at suitable intervals along the machine. The arms 11 at opposite sides of the machine are arranged in pairs, each pair being fixed upon a rock shaft 12. Rigid with each rock 70 shaft is an arm 13, the several arms 13 being connected by means of a rod 14 so that all of the arms 11 are caused to rise and fall simultaneously. The parts thus far described are of usual construction and may be 75 modified without departure from the invention herein disclosed.

A counterweight 15 (Fig. 4) attached to each of the rock shafts 12 tends to raise the ring rails. A build motion of any suitable 80 construction cooperates with the counterweights to produce the upward and downward movement of the ring rails in the normal operation of the machine. Herein is shown a combination warp and filling builder of well-known character. Said builder comprises a builder arm 16 (Fig. 6) pivoted at 17 to a stationary part of the framework. On the builder arm 16 is mounted a roller 18 that bears against a filling cam 19 which 85 is splined upon a shaft 20. The shaft 20 is driven by means of the change-speed gear train illustrated in Fig. 8. A filling arm 21 is pivoted to the builder arm 16 at 22 and lies in contact with a roller stud 23 on a rack 24. Said rack is slidably mounted on the builder arm 16 to move toward and away from the axes 17 and 22. The rack 24 meshes with a worm 25 which is rotatably mounted in the builder arm 16, said worm 90 being intermittently and slowly rotated in the normal operation of the spinning machine by well-known means not herein shown in detail, so as to cause the roller stud 23 to move toward the axes 17 and 22. A chain 95 26 connected to a hook 27 on the arm 21 extends over a guide sheave 28 and thence to the adjacent arm 13 (Fig. 4). The counterweights 15 acting through the arms 13 and the chain 26 hold the roller stud 18 100 against the cam 19.

In the rotation of the filling cam 19 the arms 16 and 21 are swung, thereby causing the ring rails 7 to rise and fall and thus to lay the yarn on the revolving bobbins. 115 As the rack 24 moves toward the axis 22, the arm 21 rises with relation to the arm 16, thereby causing the ring rails 7 to rise gradually so as to cause the yarn masses on the bobbins to lengthen in the well-known manner. When the yarn masses *a* have been completed, mechanism to be now described is operated to cause the automatic performance of certain operations preparatory to the doffing of the bobbins. These operations 120 125 consist of the formation of a small yarn mass *b* on the upper end of each bobbin above the yarn mass *a*, the lowering of the ring rails 7 to doffing position, the winding of the correct amount of yarn on the lower 130

end of the bobbin, the spinning of the proper amount of slack yarn, and the stoppage of the machine.

A transverse rock shaft 29 mounted in the machine framework carries a treadle 30 which is held in normal position by means of a tension spring 31. The normal position of the treadle is determined by contact of the treadle arm with the end frame of the machine. On the shaft 29 is fixed a fork 32 which engages the hub of the filling cam 19. When the yarn masses *a* have been completed, the operator depresses the treadle 30, thereby moving the cam 19 out of the vertical plane of the roller 18, whereupon the counterweights 15 cause said roller to rise until it stops against the hub of the cam, the ring rails at the same time being raised until they are in the plane indicated by the dotted lines in Fig. 6.

To prevent the ring rails from rising so rapidly as to break the threads, we provide the following described mechanism. 33 (Fig. 7) is a shaft which is slowly driven from the shaft 6 by means of the chain belt 34 and the gear train illustrated in Fig. 8. The shaft 33 is connected by means of bevel gears 35 to a shaft 36 to which is secured a disk 37 carrying a dog 38. A tension spring 39 holds the dog 38 in engagement with a ratchet wheel 40 that is rotatably mounted on the shaft 36. Rigid with the ratchet wheel 40 is a pinion 41 that meshes with a segment 42 carried by an arm 43 which is fixed on the adjacent shaft 12. The shaft 36 is driven in the direction indicated by the arrow in Fig. 7. It will be seen that when the filling cam 19 is moved off the roller 18, the action of the counterweights 15 in raising the ring rails will be restrained by the dog 38. The counterweights cause the segment 42 to turn the ratchet wheel 40 until a tooth thereof stops against the dog 38 and thereafter the ratchet wheel turns at the same rate as the shaft 36.

It may be here stated that the normal operation of the build motion is not interfered with by the dog 38, the travel of said dog being sufficiently rapid so that it does not restrain the rotation of the ratchet wheel 40 when the ring rails rise in the normal building operation.

The ring rails having been raised by the counterweights 15 until they reach the plane indicated by the dotted lines in Fig. 6, the continuing operation of the machine causes yarn *b* to be wound around the upper end of the bobbins above the yarn mass *a*, the yarn mass *b* being connected to the yarn mass *a* by a strand *c* (Fig. 10).

The depression of the treadle 30 also sets in operation mechanism which lowers the ring rails to doffing position as soon as sufficient yarn *b* has been wound upon the upper ends of the bobbins. This mecha-

nism comprises a winding drum 44 rotatably mounted upon the shaft 33. A cable 45 is fixed at one end to the winding drum 44, the other end of the cable being attached to one end of a tension spring 45^a which is anchored to a suitable fixed point and is capable of considerable extension. The cable runs over a guide sheave 46 and through an opening 47^a in an arm 47 which is fixed upon the adjacent shaft 12. A clutch member 48 (Fig. 7) is splined upon the shaft 33 and is adapted to engage a clutch face 49 on the winding drum 44. 50 is a fork fixed upon the rock shaft 29 and engaging the hub of the clutch member 48. 80 Depression of the treadle 30 causes the winding drum 44 to revolve with the shaft 33, thereby causing the cable 45 to be partially wound up on said drum. By the time sufficient yarn *b* has been wound on 85 the bobbins, a collar 45^b on the cable 45 has come into contact with the arm 47, whereupon the continuing movement of the cable causes the shafts 12 to turn in the direction to lower the ring rails to a point 90 slightly below the lower limit of the normal traverse. Such movement of the shafts 12 also allows the builder arm 16 and the filling arm 21 to descend somewhat below their normal position and hence out of the way 95 of the cam 19 when the latter is subsequently slid into normal position by the spring 31. In the descent of the ring rails, a strand *d* is wound around the yarn mass *a*. The descent of the ring rails is limited in 100 any usual or suitable way, as by means of a lug 14^a (Fig. 4) located on the rod 14 in position to stop against a portion 51 of the framework of the machine. When the ring rails reach their lower limit of movement, 105 they are automatically locked in such position by suitable means, as, for example, that shown in Figs. 4 and 5. 14^b is a collar fixed to the rod 14. 14^c is a latch pivoted to a suitable part of the machine frame in position to drop behind the collar 14^b when the ring rails reach the doffing position. One side of the collar is tapered to push the latch 14^c aside as the ring rails approach the lower limit of their movement. When 110 in locking position the latch is supported against the pressure of the collar by a bracket 14^d. The latch may be manually withdrawn by suitable means such as a rod 14^e.

After the ring rails have been locked in doffing position, the operator releases the treadle, the spring 45^a restoring the winding drum 44 and collar 45^b to normal position. Any rotation of the shaft 33 which may occur after the lug 14^a strikes the stop 51 merely causes the clutch member 48 to slip past the clutch face 49 on the winding drum, the clutch teeth being sufficiently 125 interlocked to allow such slippage.

As the ring rails reach the limit of their downward movement, means is actuated to throw in a low-speed drive for the machine. There is a stud 52 (Fig. 3) fixed to one of the arms 11 at the drive end of the machine, said stud having an opening through which a rod 53 extends freely. 54 is a nut on the rod 53 below the stud 52. The upper end of the rod 53 is pivoted to a latch 55 which is pivoted at 56 and has a locking shoulder 57 (Fig. 14) that is normally engaged by one of the arms of a lever 58, said lever being pivoted at 58a. A tension spring 59 (Fig. 14) normally holds the latch 55 in engagement with the lever 58. 60 is a tension spring connected to the lever 58 and normally restrained by the latch 55. The other arm of the lever 58 bears against a stop collar 61 on a slidable belt shifter rod 62. The loop 63 of the belt shifter engages a drive belt 64. Said belt is arranged to run upon a tight pulley 65 and a loose pulley 66 mounted upon the shaft 6. Back gearing is provided for communicating power from the belt 64 when the latter is on the loose pulley, to the tight pulley 65. Said back gearing is thrown into operation by means including a lever 67, the arm 68 of which is engaged by the forked end of the lever 58. The arm 69 of the lever 67 engages the forked arm 70 of a lever 71. The arm 72 of the lever 71 is connected by means of a link 73 to an arm 74 which is pivotally mounted upon a sleeve 75 (Fig. 9), said sleeve being fixed in bracket portions 76 and 77 provided in the machine framework. Pivotally mounted upon the sleeve 75 is a bracket 78 (Fig. 9) that rotatably supports a shaft 79. On said shaft is fixed a wheel 80 adapted to engage the drive belt 64 when said belt is running upon the loose pulley 66. Rigid with the shaft 79 is a pinion 81 that meshes with a spur gear wheel 82 which is fixed upon a shaft 83 that is rotatably mounted in the sleeve 75. Upon the other end of the shaft 83 is a pinion 84 that meshes with a spur gear wheel 85 which is rotatably mounted upon a shaft 86 carried by a bracket 87. The bracket 87 is pivotally mounted upon the sleeve 75. Upon the shaft 86 is fixed a disk 88 having a slot 89 (Fig. 13) into which extends a pin 90 set in the spur gear wheel 85. To the shaft 86 is fixed a wheel 91, the periphery of which is covered with leather or other suitable friction material. The friction wheel 91 is arranged to engage the periphery of the tight pulley 65 when the wheel 80 engages the drive belt 64. Rigid with the brackets 78 and 87 are upstanding arms 92 and 93, respectively, which are engaged by the opposite ends of a lever 94, said lever being pivoted upon an arm 95 which is pivoted on the sleeve 75. Rigid with the arm 95 is an arm 96 that normally

stands against a stop 97. On the arm 96 is pivoted a dog 98 (Fig. 12) that normally bears against the offset portion 99 (Fig. 16) of an arm 100 which is rigid with the arm 74. 101 is a stop on the arm 100 to limit downward movement of the dog under the action of the spring 102.

Normally the weight of the brackets 78 and 87 and the parts carried thereby holds the arm 96 against the stop 97, the dog 98 being in contact with the portion 99 of the arm 100. When the latch 55 is disengaged from the lever 58, the spring 60 moves the arm 100 in the direction to press the wheels 80 and 91 against the drive belt 64 and the tight pulley 65, respectively. At first the momentum of the machine tends to drive the wheel 91 and the disk 88, the disk exerting its force against the pin 90. Slippage thereupon occurs between the tight pulley 65 and the wheel 91, or between the drive belt 64 and the wheel 80, or between both of the wheels 80 and 91 and their respective contacting elements, until the rotation of the shaft 6 due to the momentum of the machine has been checked. The back gearing thus acts as a brake to slow down the machine promptly to the speed determined by said back gearing.

Upon the stoppage of the ring rails in their lowest position, a few coils of yarn *e* are wound upon the lower ends of the bobbins. To distinguish the coils *e* from the yarn mass *a*, the former are indicated by heavy lines in Fig. 10. By the time sufficient yarn *e* has been wound, the speed of the machine will have been reduced to the speed determined by the back gearing, which is preferably just below that at which the yarn balloons; i. e., the low speed is such that the strand of yarn *f* (Fig. 2) running from the drawing rolls to the traveler *g* on the spinning ring *h* does not balloon, but, on the contrary, comes into contact with the yarn on the bobbin. By reason of such contact, said strand and the traveler are carried around with the bobbin, and consequently the yarn produced by the drawing rolls during the slow operation of the spinning machine is not wound on the bobbin, but instead accumulates as slack between the drawing rolls and the traveler. The strand *f* kinks at one or more points, as indicated at *k* in Fig. 2.

Means is provided for disengaging the dog 98 from the portion 99 of the arm 100, when the predetermined amount of slack yarn has been spun. This means comprises a pawl 103 (Fig. 13) pivotally mounted on the disk 88 and having a finger 104 which is held in contact with the pin 90 by a spring 105. When the pin 90 moves into contact with the leading end wall of the slot 89, the pawl 103 is swung into position to engage a

ratchet wheel 106 fixed upon a shaft 107 which is rotatably supported in the bracket 87. On one end of the shaft 107 is a crank arm 108 carrying a pin 109 which is arranged to engage an extension 110 of the dog 98. A torsion spring 111 normally holds the pin 109 against the lower side of the extension 110. 112 is a detent or locking pawl which is pivoted on the bracket 87 in position to engage the ratchet wheel 106. Said detent is normally held away from the ratchet wheel by a stop 113 on the frame engaging an extension 114 of the detent. When the bracket 87 is moved by the spring 15 60, the detent 112 is placed in contact with the ratchet wheel by a tension spring 115 connected at one end to the extension 114 and at its other end to a post 116 on the bracket 87. The pawl 103 being moved into 20 effective position by the pin 90 when the braking function of the low-speed drive has been fulfilled, it will be seen that the movement of the throw-out pin 109 begins approximately simultaneously with the production of slack yarn, and hence the amount 25 of slack yarn is not affected by variations in the amount of slippage between the brake elements.

The operation is as follows: When the 30 bobbins are to be doffed, the operator depresses the treadle 30 whereupon the rails are raised above the normal traverse. After a small yarn mass *b* has been spun on the upper end of each bobbin for engagement by 35 an end-finding device (not shown), the ring rails are automatically lowered to a plane below the normal traverse. As the ring rails approach said plane the projection 52 (Fig. 3), acting through the rod 53, disengages the latch 55 from the lever 58, whereupon the spring 60 shifts the drive belt 64 from the tight pulley 65 to the loose pulley 66, and swings the brackets 78 and 87 into position to press the wheel 80 against the 40 drive belt and the wheel 91 against the tight pulley 65. Power is thereby transmitted from the belt 64, through the wheel 80, shaft 79, gears 81 and 82, shaft 83, gears 84 and 85, pin 90, disk 88, shaft 86 and wheel 91 to 45 the wheel 65, the wheel 91 acting first as a brake and thereafter driving the machine at low speed. Before the speed has been fully reduced, sufficient yarn *e* will have been wound upon the lower ends of the bobbins, 50 the ensuing low-speed operation of the machine causing the production of a slack yarn. When reversal of torque occurs, the pin 90 moves into engagement with the leading end wall of the slot 89, thereby swinging the 55 pawl 103 into position to engage the ratchet wheel 106. As the gear wheel 85 and the disk 88 revolve, the pawl 103 turns the ratchet wheel step by step, thus swinging the 60 crank pin 109 until finally it strikes the

upper side of the extension 110 and rocks 65 the dog 98 out of contact with the portion 99 of the arm 100. Gravity thereupon causes the brackets 78 and 87 to swing downwardly until the bracket 87 strikes the stop 97, the end of the dog 98 overlying the 70 portion 99. In such downward movement of the brackets, the extension 114 strikes the stop 113 and withdraws the detent 112 from the ratchet wheel 106, whereupon the torsion spring 111 restores the crank pin 109 to 75 contact with the lower side of the extension 110. The throw-out mechanism 103, 106, 108 is arranged to stop the machine as soon as the proper amount of slack yarn has been spun. In the ensuing doffing operation, all 80 or most of the yarn *e* will slip off the bobbin. Hence, when the coils *b* are stripped from the bobbin, there will not be a piece of yarn on the lower end of the bobbin nor a long strand *d* to cause trouble in the loom or 85 other apparatus for which the bobbin is intended.

It will be seen that the several operations preparatory to doffing take place automatically when the treadle 30 is depressed, the ring 90 rails being first raised for the spinning of a small yarn mass for end-finding purposes and then lowered for the winding of a few turns of yarn for doffing purposes on the lower end of the bobbin, and for the spinning 95 of a little slack yarn, after which the machine stops. The descent of the ring rails from the end-finder-coil spinning position to the doffing position is effected at such speed that the shortest practicable strand is produced between the end-finder coil and the 100 doffing coil.

When the machine is ready to be again set in motion, the operator shifts the belt 64 to the tight pulley by means of the usual 105 hand lever (not shown), the lever 58 being thereby moved into the position shown in Fig. 9, where it is retained by the latch 55. Such movement of the lever 58 raises the arm 100 far enough to allow the dog 98 to 110 spring down behind the portion 99, the dog being supported behind said portion by the lug 101.

The invention is not limited to the construction and arrangement herein disclosed, 115 as various modifications and reorganizations may be effected without departing from the spirit and scope of the invention as defined in the appended claims.

We claim as our invention:

1. A spinning machine having, in combination, a ring rail, a drive shaft, a tight pulley and a loose pulley on said shaft, a drive belt arranged to run on said pulleys, a shifter for the belt, a wheel arranged to 125 engage the belt when the latter is on the loose pulley, a wheel arranged to engage the tight pulley at such time, means for

- communicating power from the first mentioned wheel to the other, mechanism for placing said wheels in contact with said belt and tight pulley, a spring for actuating 65 said mechanism and said belt shifter, a detent for the spring, and means actuated by the ring rail for withdrawing the detent.
2. A spinning machine having, in combination, a spinning element, a drive shaft, 70 a tight pulley and a loose pulley on said shaft, a drive belt arranged to run on said pulleys, a shifter for the belt, reduction gearing arranged to coact with the belt and the tight pulley, mechanism for operating 75 said reduction gearing, a spring for actuating said mechanism and said belt shifter, a detent for the spring, and means actuated by said spinning element for withdrawing the detent.
3. A spinning machine having, in combination, spindles, a shaft and connections for rotating the spindles at normal speed, a 80 ring rail arranged to be lowered for the spinning of yarn upon the lower ends of the bobbins, and means controlled by the lowering of the ring rail for driving said shaft at a lower speed for a predetermined length of time.
4. A spinning machine having, in combination, spindles, a shaft and connections for rotating the spindles at normal speed, a ring rail arranged to be lowered for the spinning of yarn upon the lower ends of the bobbins, and means automatically 85 thrown into operation in such lowering of the ring rail for driving said shaft at a lower speed for a predetermined length of time.
5. A ring spinning machine having, in combination, a ring rail; a builder motion comprising means tending to raise the ring rail, a builder arm, a cam for moving the builder arm, a filling arm movably connected to the builder arm, and a connection between the filling arm and the ring rail; and power-driven means independent of the builder motion for lowering the ring rail to doffing position.
6. A spinning machine having, in combination, spindles, a shaft and connections for rotating the spindles at normal speed, a ring rail arranged to be lowered for the spinning of yarn upon the lower ends of the bobbins, and means controlled by the ring 95 rail for driving said shaft at a lower speed.
7. A spinning machine having, in combination, a high speed drive, a low speed drive, a ring rail arranged to descend below the normal traverse, means controlled by abnormal descent of the ring rail for replacing the high speed drive with the low speed drive, and means for throwing out the low speed drive after a predetermined length of time.
8. A ring spinning machine having, in combination, a ring rail; a builder motion comprising means tending to raise the ring rail, a builder arm, a cam for moving the builder arm, a filling arm movably connected to the builder arm, and a connection between the filling arm and the ring rail; a power-driven winding drum; and a cable connected to said drum and adapted to act upon the ring rail to lower the latter to doffing position.
9. A spinning machine having, in combination, a ring rail, a winding drum, a cable connected at one end to the winding drum, a spring connected to the other end of the cable for moving the cable in opposition to the winding drum, operating connections between the cable and the ring rail, and means for rotating the winding drum to lower the ring rail to doffing position.
10. A spinning machine having, in combination, a ring rail, a winding drum, a flexible connection between the winding drum and the rail, a drive shaft, and means driven from said shaft for rotating the winding drum to lower the ring rail to doffing position.
11. A spinning machine having, in combination, a ring rail, a builder motion for traversing the ring rail, said rail tending to rise, power-driven means for lowering the ring rail to doffing position, and manipulative means for disabling the builder motion and throwing said lowering means into action.
12. A spinning machine having, in combination, a ring rail arranged to descend below the normal traverse, a low speed drive arranged to be placed in action by abnormal descent of the ring rail, and means for throwing out said drive after a predetermined length of time.
13. A spinning machine having, in combination, a ring rail arranged to travel beyond the normal traverse, a low speed drive arranged to be placed in action by abnormal travel of the ring rail, and means for throwing out said drive after a predetermined length of time.
14. A spinning machine having, in combination, a ring rail arranged to descend below the normal traverse, a drive controlled by abnormal descent of the ring rail, and means for throwing out said drive after a predetermined length of time.
15. A spinning machine having, in combination, a ring rail arranged to descend below the normal traverse, and a low speed drive controlled by abnormal descent of the ring rail.
16. A spinning machine having, in combination, a ring rail arranged to travel beyond the normal traverse, and a low speed drive controlled by abnormal travel of the ring rail.

17. A spinning machine having, in combination, a ring rail arranged to descend below the normal traverse, and a drive for the machine controlled by abnormal descent of the ring rail.
18. A spinning machine having, in combination, a ring rail arranged to travel beyond the normal traverse, and a drive for the machine controlled by abnormal travel of the ring rail.
19. The combination of a rotary spindle to support a bobbin, a spinning ring having a normal traverse longitudinally of the spindle, said ring being arranged to travel below said normal traverse, and a low speed drive mechanism for imparting a predetermined amount of rotation to the spindle while the ring is in such abnormal position.
20. A spinning machine having, in combination, a drawing roll, a bobbin spindle, a spinning ring, a traveler on the ring, means for driving the drawing roll and the spindle at winding speed, and means acting after the formation of the main yarn mass upon the bobbin to drive the drawing roll and the spindle at such reduced speed that ballooning of the yarn between the roll and the traveler does not occur.
21. A spinning machine having, in combination, a drawing roll, a bobbin spindle, a spinning ring, a traveler on the ring, and means for driving the drawing roll and the spindle after the formation of the main yarn mass thereon for a predetermined length of time at subnormal speed so that ballooning of the yarn between the roll and the traveler does not occur.
22. A spinning machine having, in combination, spinning elements, means to drive the spinning elements at winding speed, and means to brake the spinning elements, and thereafter drive them at less than winding speed.
23. A spinning machine having, in combination, spinning elements, means to drive the spinning elements at winding speed, and means acting automatically after the formation of the main yarn mass to drive the spinning elements at less than winding speed for a predetermined length of time to produce slack yarn.
24. A spinning machine having, in combination, a rotary spindle for a bobbin, a spinning ring, means to raise the ring into position to spin an end-finder coil on the upper end of the bobbin, means to lower the ring into position to spin a doffing coil on the lower end of the bobbin, means to lock the ring in the last mentioned position, and means to drive the spindle at sub-balloon speed.
25. A spinning machine having, in combination, a rotary spindle for a bobbin, a spinning ring, means for raising the ring into position to spin an end-finder coil on the upper end of the bobbin and for then lowering the ring into position to spin a doffing coil on the lower end of the bobbin, and means controlled by said raising and lowering means for driving the spindle at sub-balloon speed for a predetermined length of time.
26. A spinning machine having, in combination, a rotary spindle for a bobbin, a spinning ring tending to rise, a builder motion for normally traversing the ring, means to disable the builder motion whereby the ring rises into position for the spinning of an end-finder coil on the upper end of the bobbin, means automatically actuated to lower the ring from such elevated position to a position for spinning a few turns of yarn on the lower end of the bobbin, means to lock the ring in the last mentioned position, and means controlled by the lowering means for driving the spindle at sub-balloon speed for a predetermined length of time.
27. A spinning machine having, in combination, a ring rail, a builder arm operatively connected to the rail, a laterally slideable cam, means for holding the arm against the cam, a shaft, a winding drum rotatively mounted on the shaft, a flexible connection between the winding drum and the rail, a clutch element on the shaft arranged to engage the winding drum, a rock shaft, forks on the rock shaft for sliding said cam and clutch member, manipulative means for turning the rock shaft in one direction, and means for turning the rock shaft in the opposite direction.
28. A spinning machine having, in combination, a ring rail, a builder arm operatively connected to the rail, a laterally slideable cam, means for holding the arm against the cam, a winding drum, a flexible connection between the winding drum and the rail, means for rotating the drum including a clutch member, and manipulative means for sliding said cam and clutch member.
29. A spinning machine having, in combination, a ring rail, a builder arm operatively connected to the rail, a cam movable out of operative position, means for holding the arm against the cam, a shaft, a winding drum rotatively mounted on the shaft, a flexible connection between the winding drum and the rail, a clutch element on the shaft arranged to engage the winding drum, a rock shaft, forks on the rock shaft for moving said cam out of operative position and for throwing in said clutch member, manipulative means for turning the rock shaft in one direction, and means for turning the rock shaft in the opposite direction.
30. A spinning machine having, in combination, a ring rail, a builder motion for effecting a normal traverse of the ring rail, and means for effecting an abnormal trav-

erse of the ring rail including a rotary shaft, a winding drum loosely mounted on the shaft, a flexible element connected to the winding drum and operatively connected to the ring rail, and means operable by the operator for connecting and disconnecting the shaft and the winding drum.

31. A spinning machine having, in combination, a ring rail, a builder motion for effecting a normal traverse of the ring rail, and means for effecting an abnormal traverse of the ring rail including a rotary shaft, a winding drum, means for rotating the winding drum, a flexible element connected to the winding drum and operatively connected to the ring rail, and means for connecting and disconnecting the winding drum and said rotating shaft.

32. A spinning machine having, in combination, a ring rail, a rock shaft operatively connected to the ring rail, a counterweight tending to turn the shaft in the direction to raise the ring rail, a gear segment on the rock shaft, a pinion meshing with the segment, a wheel rotatable on the axis of the pinion, a pawl carried by said wheel, a ratchet wheel connected to the pinion and engaged by said pawl, and means for rotating the pawl-carrying wheel backwardly with reference to the ratchet wheel.

33. A spinning machine having, in combination, a ring rail, means tending to raise the ring rail, a ratchet wheel geared to the raising means, a wheel rotatable on the axis of the ratchet wheel, a pawl carried by the second mentioned wheel and engaging the ratchet wheel, and means for rotating the pawl-carrying wheel backwardly with reference to the ratchet wheel.

34. A spinning machine having, in combination, a ring rail, a builder arm operatively connected to the rail, a cam, means for holding the arm against the cam, means for causing relative disengaging movement between the arm and the cam, and means for restraining the resultant rise of the rail, but permitting a slow upward movement thereof.

35. A spinning machine having, in combination, a ring rail, a builder arm operatively connected to the rail, a cam, means for holding the arm against the cam, means for laterally moving the cam out of operative relation to the arm, and means for restraining the resultant rise of the rail but permitting a slow upward movement thereof.

36. A spinning machine having, in combination, a ring rail, a builder motion operatively connected to the rail and including means tending to raise the rail, means for operating the builder motion to release the

raising means to action, and means for restraining the resultant rise of the rail but permitting a slow upward movement thereof.

37. A spinning machine having, in combination, a ring rail tending to rise, a builder motion for traversing the ring rail, and power means under the control of the operator for lowering the ring rail below the normal traverse.

38. A spinning machine having, in combination, a ring rail, a builder arm operatively connected to the rail, a cam, means for holding the arm against the cam, and means for laterally moving the cam out of operative relation to the arm whereby the latter is permitted to rise.

39. A spinning machine having, in combination, a ring rail, a builder arm operatively connected to the rail, a cam, means for holding the arm against the cam, and means for causing relative disengaging movement between the arm and the cam whereby the arm is permitted to rise.

40. A spinning machine having, in combination, a ring rail, a builder motion comprising a counterweight and a cam, a lowering means for the rail, and means for disabling the cam to permit the counterweight to raise the rail, and for subsequently placing the lowering means in action.

41. A spinning machine having, in combination, a ring rail, a winding drum, a cable connected at one end to the winding drum, means connected to the other end of the cable for moving the cable in opposition to the winding drum, a member operatively connected to the ring rail, said cable being movable longitudinally relative to said member, a device on the cable adapted to engage said member to move the ring rail to doffing position, and means for rotating the winding drum.

42. A spinning machine having, in combination, spinning elements, means to drive the spinning elements at winding speed to form the main yarn mass and a doffing coil, and means acting automatically after the formation of the doffing coil to drive the spinning elements at less than winding speed for a predetermined length of time to produce slack yarn.

43. A spinning machine having, in combination, spinning elements, and means for automatically driving the spinning elements at less than winding speed for a predetermined length of time to produce slack yarn.

In testimony whereof we have hereunto set our hands.

HOWARD D. COLMAN.
BURT A. PETERSON.
